AIR OUTLET DEVICE FOR VENTILATING SYSTEMS

Friedrich Honerkamp, New York, N. Y., assignor to Anemostat Corporation of America, New York, N. Y., a corporation of Delaware

Application October 19, 1949; Serial No. 122,312

4. Claims. (Cl. 98—40)

1

This invention relates to air distributing devices for effecting diffused delivery of air from air supply ducts into rooms and other enclosures for heating, cooling, ventilating or other purposes, and has particular reference to improvements in air distributing devices of the known general type comprising a plurality of successively smaller, open-ended, hollow, forwardly flaring members which are disposed successively inwardly of and in spaced apart relationship to one another, whereby air delivered forwardly through the device is divided into a plurality of separate streams and is deflected more or less laterally from the device by said members so that the air is delivered into the room or other enclosure in diffused form over a substantial portion of the area thereof.

In devices of the type referred to the flaring members may be of either frusto-conical form or frusto-pyramidal form. The latter form is desirable in many instances but, as heretofore produced, the frusto-pyramidal members have had more or less sharply peaked ridges at their corners where the ends of their flat, inclined sides meet, and these ridges have had the effect of dividing the air which is delivered toward the corners of the devices and of deflecting it toward the sides of the devices. As a consequence, practically all of the air which has been supplied to devices of the type referred to as heretofore constructed and which have flaring members of frusto-pyramidal form, has been delivered from the sides of the devices and there has been little or no air delivered from the corners of the devices, which has been highly disadvantageous since it usually is desirable to have substantially equal amounts of air delivered in all directions laterally from such devices.

Accordingly, the object of the present invention is to provide a device of the character referred to wherein the flaring members thereof are of frusto-pyramidal form and wherein frusto-conical or substantially frusto-conical members are combined with said pyramidal members in such manner that substantially equal amounts of air are delivered in all directions laterally from the device despite the presence of more or less sharply peaked ridges at the corners of the pyramidal members where the ends of their flat, inclined sides meet.

With the foregoing general object in view, the invention consists in a device of the character referred to which embodies the novel features of construction, combination and arrangement of parts as are illustrated by way of example in the

2

accompanying drawings and as will be herein-after more fully described and claimed.

In the accompanying drawings, wherein the characters of reference denote corresponding parts in the different views:

Fig. 1 is a rear elevation of an air distributing device constructed in accordance with the invention;

Fig. 2 is a central longitudinal section through the device.

Referring to the drawings in detail, it will be observed that the present air distributing device, according to the embodiment thereof specifically illustrated, is of a known general type comprising a plurality of successively smaller, open-ended, hollow, flaring members 10 of frusto-pyramidal form which flare toward the front end F of the device, taper toward the rear end R of the device, and which are disposed successively inwardly of and in spaced apart relationship to one another to provide a plurality of successively smaller, forwardly flaring air passageways 11 therebetween.

A neck 12 extends rearwardly from the rear end of the larger or outermost member 10 to adapt the device for connection with an air supply duct, and when air is supplied through said neck it is divided by the members 10 into a plurality of separate streams which flow through the passageways 11 and are deflected laterally from the device by impingement against the rear faces of said members. The air thereby is delivered from the device in diffused form throughout a substantial area forwardly and laterally relative to the device.

At the meeting ends of the flat, inclined side walls of the members 10 are more or less sharp ridges 13 which, in ordinary devices of the type illustrated, divide supplied air directed forwardly toward the corners of said members and deflect it toward the sides of said members. Consequently, in ordinary devices of the type illustrated, practically all of the air is delivered from the sides of the devices and little or no air is delivered from the corners of the devices, which is highly disadvantageous since it is desirable to have substantially equal amounts of air delivered in all directions laterally from such devices.

The members 10, of which there may be any desired number, may have equal or unequal amounts of flare, as desired, and their rear ends may be successively smaller so that they are disposed successively inwardly of one another, as shown, whereby air is delivered through each of the passageways 11. Alternatively, the rear end

of any of the members 10 may, in accordance with known practice and as disclosed for example in Kurth Patent No. 2,142,134 of January 3, 1939, be smaller than the rear end of the next smaller member so that its rear end is disposed inwardly with respect to the rear end of the said next smaller member so as to cause the supplied air to flow across the mouth or rear end of such passageway, thereby to cause a rearward or aspirating flow of air through such passageway and consequent mixing within the device of part of the supplied air with part of the room or other enclosure air. Moreover, the present device may be modified in various other ways in accordance with known practices. Essentially, however, the present invention resides in combining with certain or all of the flaring members 14 which act as deflectors for the supplied air, other flaring air deflector members or rings 14 of frusto-conical or substantially frusto-conical form which are so related to the flaring members 10 as to cause practically the same amount of air to be delivered from the corners of any given passageway 11 as from the sides of such passageway.

In accordance with the invention and as illustrated in the drawings, the frusto-conical flaring members 14 are disposed, rearwardly of the pyramidal flaring members 10, respectively, in the path of flow of air supplied through the neck 12, and are of such lengths or depths and diameters and have such amounts of flare that they act to deflect the supplied air over at least the rear portion of said members 10 and preferably well toward the front portion thereof, whereby the sharply peaked ridges 13 of said members 10 have little effect in dividing and deflecting the air. In this connection the rear or smaller end of each of the flaring members 14 preferably is, as illustrated, of approximately the same diameter as the opening in the rear end of the member 10 immediately forwardly of said member 14, whereby said member 14 intercepts and deflects as much of the supplied air as practicable substantially without interfering with flow of the supplied air through the opening in the rear end of said immediately forwardly disposed member 10. Also in this connection it will be noted that due to the square or other polygonal shape of the rear ends of the members 10 and to the circular or substantially circular shape of the members 14, the mouths or rear ends of the passageways 11 are more widely open at their corners and are progressively constricted toward points midway between their corners by the members 14, whereby the supplied air is permitted to flow more freely toward the corners of the passageways 11 than toward points midway between said corners and is, in fact, urged by the members 14 to flow in this manner, whereby there is attained substantially as much air flow from the corners of said passageways 11 as from points between their corners. Indeed, the size, flare and other characteristics of any of the members 14 may be such in relation to the dimensions of the passageway 11 through which it deflects the supplied air as to cause substantially equal amounts of air to flow through all portions of said passageway.

As will be understood, the present device may include only two members 10 and a single member 14 for deflecting air over the smaller of said members 10, in which event the member 14 need not be open at its smaller or rear end. As will also be understood, the smaller of the members

14 may be closed at its smaller or rear end in any instance where it may be permissible or desirable not to have air delivered through the smaller or innermost of said members 10. Furthermore, it will be understood that in any given device of the present type, an air deflecting member or members 14 may be combined with only a single one or more of the members 10 rather than with each of said members 10.

10 As will be understood, the members 10 may be connected together in spaced apart relationship to each other either by means of struts in accordance with known practice or in any other suitable manner, and the members 14 may be mounted between said members 10 either by means of such struts or in any other suitable manner.

20 As will be apparent, the supplied air initially is deflected by the members 14 rather than by the inner or rear end portions of the members 10 and its deflection primarily is controlled by said members 14 so that, despite the pyramidal form of the members 10 and the ridges 13 at their corners, there may be attained, by a proper selection of the sizes and flare of the members 14, delivery of substantially equal amounts of air from the corners as from other portions of any or all of the passageways 11.

25 From the foregoing description considered in connection with the accompanying drawing, it is believed that the construction and operation of the present air outlet device will be clearly understood and that its advantages will be appreciated. It is desired to point out, however, that while only a single structural embodiment of the invention has been illustrated and described, the same is readily capable of specifically different structural embodiments within its spirit and scope as defined in the appended claims.

30 I claim:

35 1. An air distributing device comprising an outermost hollow forwardly flaring member open at its rear end for supply of air to the device and open at its front end for escape of air from the device, the front end of said member being of rectangular shape, a second member similar to said outermost member disposed within and spaced from said outermost member, said second member being of forwardly flaring frusto-pyramidal form and being disposed symmetrically relative to said outermost member, and a forwardly flaring member of frusto-conical form disposed within said outermost member rearwardly of said second member to effect deflection outwardly with respect to said second member of air supplied to the device, the front end of said frusto-conical member being of a diameter greater than the width of the rear end of said frusto-pyramidal member.

40 2. An air distributing device comprising an outermost hollow forwardly flaring member open at its rear end for supply of air to the device and open at its front end for escape of air from the device, the front end of said member being of rectangular shape, a second member similar to said outermost member disposed within and spaced from said outermost member, said second member being of hollow open-ended forwardly flaring frusto-pyramidal form and being disposed symmetrically relative to said outermost member, and a hollow open-ended forwardly flaring member of frusto-conical form disposed within said outermost member rearwardly of said second member to effect deflection outwardly with respect to said second member of air sup-

plied to the device, the rear end of said frustro-conical member being of a diameter not greater than the width of the rear end of said frustro-pyramidal member.

3. An air distributing device comprising an outermost hollow forwardly flaring flat-sided member of frustro-pyramidal form open at its rear end for supply of air to the device and open at its front end for escape of air from the device, a second forwardly flaring member of frustro-pyramidal form within and symmetrically disposed with respect to and spaced from said outermost member, and a forwardly flaring member of frustro-conical form disposed within said outermost member rearwardly of said second member to effect deflection outwardly with respect to said second member of air supplied to the device, the width of the space between said frustro-conical member and the sides of said outermost member being constricted toward the centers of the rear end portions of said sides of said outermost member so as to cause the supplied air to flow in substantially equal amounts through all portions of the space between said outermost member and said second member, the front end of said frustro-conical member being of a diameter greater than the width of the rear end of second member.

4. An air distributing device comprising an outermost hollow forwardly flaring flat-sided member of frustro-pyramidal form open at its

rear end for supply of air to the device and open at its front end for escape of air from the device, a second forwardly flaring member of frustro-pyramidal form within and symmetrically disposed with respect to and spaced from said outermost member, and a forwardly flaring member of frustro-conical form disposed within said outermost member rearwardly of said second member to effect deflection outwardly with respect to said second member of air supplied to the device, the width of the space between said frustro-conical member and the sides of said outermost member being constricted toward the centers of the rear end portions of said sides of said outermost member so as to cause the supplied air to flow in substantially equal amounts through all portions of the space between said outermost member and said second member, the rear end of said frustro-conical member being of a diameter not greater than the width of the rear end of said second member.
